VACUUM LIFT DEVICE

William L. Nelson, South Holland, Ill., assignor to
 United States Gypsum Company, Chicago, Ill.,
 a corporation of Illinois

Application October 20, 1939, Serial No. 300,327

3 Claims. (Cl. 294—65)

This invention relates to lift devices, and has reference more particularly to vacuum lift devices suitable for lifting and transporting sheets of flexible material, such as asbestos-cement sheet shingle stock.

In the manufacture of asbestos-cement shingles, siding and industrial sheet material of all kinds, it is customary to manufacture large sheets of the asbestos-cement stock material. After forming the sheets, they are lifted from the forming conveyor by a vacuum lift box and deposited on a conveyor which carries the sheet through the platens of a hydraulic press. A wood grain imprint is pressed onto the top surface of the sheet by the press and the conveyor then transfers the sheet to the delivery side of the press. Here another vacuum lift box engages the grained upper surface of the sheet and transfers the sheet to a skid to permit the cement to set over a period of several hours. In the vacuum lift boxes previously used, the lower surface of the box has been covered with porous screen wire backed up by suitable frame work. It has always been thought that the vacuum must be applied to the entire face of the sheet by the use of the screen wire. However, it has been found that the press of the screen on the plastic embossed surface of the sheet, leaves the imprint of the wire meshes on the protruding embossed ridges of the surface of the sheet. These wire mesh imprints on the sheet are objectionable and decrease the salability of the resulting shingles.

An object of the invention, therefore, is to provide a vacuum box in which the objectionable screen wire is eliminated and a flat sheet with peripheral vacuum applying holes is used.

Another object of the invention is to decrease the weight and improve the lifting power of a vacuum lift box.

A further object of the invention is to produce an embossed sheet of asbestos cement which is free of screen wire imprints; also to improve vacuum lift boxes and asbestos cement sheet products in other respects hereinafter specified and claimed.

Reference is to be had to the accompanying drawings forming a part of this specification, in which

Fig. 1 is a plan view of the vacuum lift box, Fig. 2 is a sectional elevation through the box taken on line 2—2 of Fig. 1,

Fig. 3 is a bottom view of the box,

Fig. 4 is a sectional elevation on an enlarged scale taken on line 4—4 of Fig. 1, and

Fig. 5 is a diagrammatic view showing the piping and other apparatus associated with the box.

Referring to the drawings by numerals, the vacuum box 10 is connected by a pipe 11 to a vacuum tank 12 having a drain valve 13. A 5 three way valve 14 is provided on the pipe 11 to apply the vacuum for lifting a sheet 15, said valve 14 also being arranged to release the vacuum to deposit the sheet at a desired point. A pipe 16 connects the tank 12 to a vacuum 10 pump 17.

The box 10 comprises transverse channel beams or frames 18, 19 and 20 secured to longitudinal channel beams or frames 21 by angle clips 22 and bolts 23. U-bars 24, preferably four 15 in number, are provided with flattened ends 25 which are secured to the frame members 18, 20 and 21 by bolts 26. A hoisting chain 27 is secured at one end to each of U-bars 24, the opposite ends of said chains being connected to a 20 ring 28. A pneumatic or other type of hoist not shown, may be attached to the ring 28 to lift the apparatus carrying a sheet of material. End channel frames 29 are secured to the ends of 25 channels 21 by angle clips 30.

Metal bars 32 extend around the periphery of the box below outstanding lower flanges 33 formed on the channel frames 21 and 29, being secured thereto by bolts 34. A longitudinal groove or air passage 35 extends along the bottom face of 30 each bar 32 and branch pipes 36 are connected at intervals to the inside of each bar 32. The branch pipes 36 join in an air manifold 37 which is joined by flexible hose 38 to the vacuum tank 12. A metal sheet 39 is secured about its periphery by screws 40 and bolts 34 to the channel flanges 33. Screws 41 secure the sheet 39 to the channels 18, 19 and 20 intermediate the edges of said sheet 39. A series of air holes 43 are formed around the periphery of sheet 39, said 40 holes registering with the grooves 35. In order to seal the box around the periphery, with the sheet of asbestos-cement shingle material 15, I attach a thick strip of medium soft rubber 45 to channels 21 and bars 32 by a metal strip 46 45 and screws 47 and 48 respectively. A strip of hard rubber 49 is interposed between the rubber strip 45 and metal strip 46 in order to back up and stiffen the rubber strip 45. The lower edge of rubber strip 45 is provided with a bevel 50 which forms a sealing edge 51 on the bottom of said strip 45. I prefer to make all metal parts, where possible, of Dow metal, a magnesium base alloy, because of its lightness and strength. Other light weight metals may of course be used. 55

It will be seen that as the sheet 39 is imperforate or air-tight inside the peripheral air holes 43, no defacing marks will be produced on the upper surface of the sheet 15, as were produced by the older type of lift box in which screen wire was used on the lower surface of the box. Furthermore, the vacuum is evenly applied over the face of the sheet 15 when the air holes 43 are arranged only around the periphery of the sheet 39, contrary to the accepted belief that air holes have to be located throughout the area of the sheet.

I would state in conclusion that, while the illustrated example constitutes a practical embodiment of my invention, I do not wish to limit myself precisely to these details, since manifestly that same may be considerably varied without departing from the spirit of the invention as defined in the appended claims.

Having thus described my invention, I claim as new and desire to secure by Letters Patent:

1. In a vacuum lift device, a substantially imperforate rigidly held sheet of material, sealing means around the periphery of said sheet for forming a substantially air-tight seal with a supported sheet of flexible material, said first sheet

being provided with a series of peripheral air holes adjacent said sealing means, and means for applying vacuum through said holes to draw said flexible sheet against said first sheet and said sealing means.

2. In a vacuum lift device, a supporting frame, a rigid bar member extending about the periphery of said frame, a substantially imperforate sheet rigidly supported by said frame and bar member, said bar member having a longitudinal slot formed in the bottom surface thereof, air holes around the periphery of said sheet and communicating with said slot, sealing means around the periphery of said frame, and means for applying vacuum to said slotted bar and sheet so as to draw a flexible sheet of material against said sealing means and said first sheet.

3. In a vacuum lift device, a sheet of rigidly held material having air holes only around the periphery thereof, means for attaching said sheet to a hoist, sealing means adjacent the periphery of said sheet, and means for applying a vacuum to said holes so as to draw a flexible sheet of material against said first sheet and said sealing means.

WILLIAM L. NELSON.
